SLEEVE ARRANGEMENT FOR GARMENTS

Rose B. Hansen, Asheville, N. C., assignor of one-tenth to Helen B. Steinbrecher

Application April 10, 1940, Serial No. 328,951

5 Claims.

(Cl. 2—93)

My invention relates to improvements in sleeve arrangements for garments of men and women alike and is especially applicable to women's golf dresses, nurses uniforms and the like where trimness of appearance coupled with freedom of arm and torso movements are prime essentials.

With the foregoing in view an object of my invention is to provide an improved free-swing connection between the sleeves and body of a garment which will permit free arm, shoulder and back movement of the wearer.

A further object is to provide such a connection which will be inconspicuous on the garment and yet will be highly efficient in use.

Other objects and advantages reside in the particular structure of the connection, combination and arrangement of the parts and in the particular mode of applying it to the garment as will be readily apparent to those skilled in the art upon reference to the drawings and following detailed description thereof.

In the drawings:

Fig. 1 is a rear elevation of a dress showing the invention applied thereto;

Fig. 2 is an enlarged, fragmentary rear elevation with parts broken away;

Fig. 3 is an enlarged fragmentary front elevation with parts broken away;

Fig. 4 is a fragmentary vertical section taken in the plane of the under arm seam;

Fig. 5 is a reduced elevation of the under piece of my improved connection showing the same applied to the garment, the outer piece of the connection being removed; and

Fig. 6 is a reduced elevation of the outer piece showing the same applied to the garment over the under piece.

Referring to the drawings in detail G indicates a garment to which my invention is applied. While I have shown the invention applied to a woman's dress, it is understood that it is applicable as well to any sleeved garment whether the same is designed to be worn by men, women or children.

The garment G has shoulder yokes 10 which are connected to a front 13 and a back 12 by seams 10a and connected to the upper parts of sleeves 11 by short seams.

My improved connection comprises two substantially identical and substantially J-shaped pieces of fabric 16 and 17 each comprising a leg and an integral pointed tail. The under piece 17 is slightly narrower than the outer piece 16 as is clearly shown in Figs. 4 and 6.

As shown in Fig. 2, the side edge and arm hole portion of the garment back 12 is not directly connected to the sleeves 11 at all but is connected by stitching 20 to the concave side edge of the under piece 17 of my connecting insert. The opposite, convex side edge portion of the under piece 17 is connected to the like edge of the outer piece 16 by stitching 18. The concave edge of the outer piece 16 is connected by stitching 11a to the rear, under and lower part of the front of the adjacent edge portion of the sleeve 11. The upper side edge portions of the garment front 13 are connected to the sleeves 11 by short seams 13a. Below the seams 13a, the remaining upper side edge portions and arm hole portions of the garment front 13 are connected to the concave edge of the tail of the under piece 17 by a continuation of the stitching 20.

The upper ends of the legs of the pieces 16 and 17 are stitched to the rear yoke seam 10a while the pointed tails thereof are joined and stitched to the lower end of the front arm seams 13a.

To anchor the connecting insert to the garment and to insure the return of the insert to its normal cross sectional V-shape after it has been extended, I anchor the under pieces 17 to the under-arm seams 14 of the garment by lines of stitching 19. It is noted that the lines of stitching 19 start at the arm hole sides of the under pieces 17 and follow the under arm seams 14 but that the stitching 19 does not entirely traverse the pieces 17. Instead, the stitching terminates short of the opposite convex edge to leave free edge portions 21. As is shown in broken lines in Fig. 4, the free edge portions 21 flex upwardly during arm, shoulder and back movement of the wearer to provide a high degree of freedom of movement. At the same time, the stitching 19 prevents the connection from being extended too far and from turning inside out. With this limitation on the extension of the connecting insert, the same returns readily to its original shape and position by gravity and/or by the natural resiliency of the fabric and no springs, elastics or other resilient members are necessary. At the same time, should it be desirable, an end of an elastic could be connected to the free edge 21 with the other end anchored to the seam 14. While I have shown a line of stitching 19 extending from the concave edge of the under piece 17, it is obvious that a stitch or two in the center of the under piece would serve equally well to accomplish the same result.

While I have shown and described what is now thought to be the preferred embodiment of my invention, it is to be understood that the same is susceptible of other forms and embodiments. Consequently, I do not intend to limit myself to the particular expression of my invention shown and described herein except as hereinafter claimed.

I claim:

1. In a garment having a front, back, arm holes and sleeves; a free-swing connecting insert between said sleeves and said garment, comprising a pair of similar and substantially J-shaped pieces of fabric, each comprising a leg and an integral tail, said pieces being superposed to provide an under and an outer piece, the upper ends of the legs of said pieces being joined and connected to a shoulder portion of said back of said garment, the concave and convex edges of each piece merging into a point at the end of the tail, said pieces being joined together throughout the length of their convex side edges, the concave side edge of said under piece being attached to an upper side edge and arm hole edge of the back of said garment and an arm hole edge of the front of said garment, the upper side edge of the front of said garment above said arm hole edge being connected to said sleeve, the concave edge of the outer piece being connected throughout its length to said sleeve and means rigidly connecting a portion of said under piece only to a side portion of said garment below said sleeve, said last named means being positioned intermediate said concave and convex edges of said under piece.

2. In a free-swing, sleeve connection for a garment, including an extensible insert substantially V-shaped in cross section, said insert having the edge of one leg connected to the garment, the corresponding edge of the other leg connected to the sleeve and having a free apex; means rigidly connecting a portion of said first leg only to a portion of said garment, said last named means being positioned intermediate said edge of said last leg and the apex of said insert.

3. In a garment having a front, back, arm holes, under arm seams, and sleeves; a free-swing connecting insert between said sleeves and

said garment, comprising a pair of similar and substantially J-shaped pieces of fabric, said pieces being superposed to provide an under and an outer piece, the upper ends of the legs of said pieces being joined and connected to a shoulder portion of said back of said garment, said pieces being joined throughout the length of their convex side edges, the concave side edge of said under piece being attached to an upper side edge and arm hole edge of the back of said garment and an arm hole edge of the front of said garment, the upper side edge of the front of said garment above said arm hole edge being connected to said sleeve, the concave edge of the outer piece being connected throughout its length to said sleeve, a line of stitching connecting a portion of said under piece to the under arm seam of said garment, said line of stitching commencing at the concave edge of said under piece and extending toward the convex edge but terminating a substantial distance from said convex edge.

4. In a free-swing, sleeve connection for a garment, including a two-piece extensible insert substantially V-shaped in cross section, the pieces of said insert being substantially identical curved strips joined together along the convex edges and ends, the concave edge of one of said pieces being connected to the arm hole and rear side edge of the back of said garment, the concave edge of the other piece being connected to the lower and rear, arm hole portions of the sleeve and means rigidly connecting a portion of said first named piece only to a side portion of said garment, said last named means being positioned intermediate said concave and convex edges of said last named piece.

5. In a free-swing sleeve connection for a garment, including an extensible insert substantially V-shaped in cross section, said insert having an edge of one leg connected to the garment, having the corresponding edge of the other leg connected to the sleeve and having a free apex; stitching rigidly connecting a portion of said first leg only to said garment, said stitching being located intermediate said edge of said first leg and the apex of said insert.

ROSE B. HANSEN.
